Augustus B. Shroughton
ATTORNEY.

UNITED STATES PATENT OFFICE.

ANDREAS BOTHE, OF ORELAND, PENNSYLVANIA, ASSIGNOR TO KLEEN PRODUCTS COMPANY, INC., OF NORTH WALES, PENNSYLVANIA, A CORPORATION OF DELAWARE.

FIBER SPOON.

Application filed January 17, 1922. Serial No. 529,995.

To all whom it may concern:

Be it known that I, ANDREAS BOTHE, a citizen of the United States, residing at Oreland, in the county of Montgomery and State 5 of Pennsylvania, have invented a new and useful Improvement in Fiber Spoons, of which the following is a specification.

The principal object of the present invention is to provide a fiber spoon which shall 10 be stiff, rigid and strong throughout its length and more especially throughout the portion of its length which includes the bowl, the handle and the union of the two. Another object of the invention is to provide a 15 fiber spoon having the characteristics referred to and which shall be not only slightly but also capable of commercial manufacture.

Other objects of the invention will appear 20 from the following description, and the invention itself will be claimed at the end hereof.

In the following description reference will be made to the accompanying drawing forming part hereof and in which—

25 Figure 1 is a front view looking at the concavity of the bowl of a spoon embodying features of the invention.

Fig. 2 is a longitudinal central section of the same, and

30 Fig. 3 is a transverse section on the line 3—3 of Figure 1.

Referring to the drawings the fiber spoon is provided with a central corrugation, hollow ridge or valley 1 which starts from a 35 point 2 midway of the length of the bowl 3 and expands sidewise and flatwise as at 4 along the rear half of the bowl and extends along the handle as at 5 and vanishes in arcuate form as at 6 at substantially the end 40 of the handle. Substantially coextensive with the corrugation or valley there is a flat border flange 7 extending around the spoon.

Evidently the appearance of the spoon is 45 attractive and slightly and the fact that the hollow ridge or valley extends substantially halfway across the bowl and to practically the end of the handle imparts great strength and rigidity to the spoon which is 50 particularly important in view of the char-

acter of the material of which it is made. The flange 7 in combination with the described valley or corrugation increases the rigidity of the spoon as a whole.

As shown in the drawing the spoon is offset from end to end in the direction of the valley. This will be understood by referring to Fig. 2 and imagining a plane perpendicular to the plane of the paper and passing through the end of the handle, generally indicated at 7, and the tip of the bowl of the spoon. The greatest offset occurs substantially at the junction of the bowl and handle. By reason of the described bowl form the spoon is structurally strong to resist pressure applied by the handle at the tip end of the bowl in the direction of its concavity. It may be said that the spoon is concave from end to end and from side to side throughout its entire extent and is lengthwise of inverted arch form. Since fiber in sheet form opposes little or no resistance to bending, the described form of the spoon is a matter of great importance since it imparts sufficient strength and rigidity which is not imparted to anything like the same extent in cases where reverse or ogee curves are employed.

It will be obvious to those skilled in the art that modifications may be made in details of construction and arrangement, for example, the end of the bowl may be notched inwards from the periphery to provide tines, without departing from the spirit of the invention which is not limited as to such matters or otherwise than as the prior art and the appended claims may require.

I claim:

1. A fiber eating implement including bowl and handle portions and having a central corrugation or valley concave in the direction of the bowl and which extends from a point midway of the length of the bowl along the rear half of the bowl and along the handle and vanishes in arcuate form at substantially the end of the handle and the implement being offset throughout from end to end in the direction of the concavity of the valley, the maximum offset occurring at the union of the handle and bowl.

2. A fiber spoon having a central corrugation or valley concave in the direction of the bowl and which starts from a point substantially midway of the length of the bowl
5 and extends along the rear half of the bowl and along the handle to substantially the end thereof and the spoon being offset through-

out from end to end in the direction of the concavity of the valley.

3. A fiber eating implement including a 10 handle and bowl and concave from end to end and from side to side throughout its entire extent and lengthwise of arch form.

ANDREAS BOTHE.
